UNITED STATES PATENT OFFICE.

JESSE C. HOWARD, OF COLUMBUS, OHIO.

WATER-MOTOR.

1,031,340.

Specification of Letters Patent.

Patented July 2, 1912.

Application filed March 22, 1909. Serial No. 484,947.

To all whom it may concern:

Be it known that I, JESSE C. HOWARD, a citizen of the United States, residing at Columbus, in the county of Franklin and 5 State of Ohio, have invented certain new and useful Improvements in Water-Motors, of which the following is a specification.

This invention relates to a fluid motor and is especially adapted for a water motor 10 to use in combination with a pump.

The object is to simplify the parts and at the same time improve the efficiency of the device.

In the appliance shown there are a minimum number of washers, thereby lessening the danger of leakage, and the parts are all so arranged that the device is extremely compact with a minimum danger of leakage, easy to assemble or repair by inexperienced 20 persons.

Figure 1 is a vertical sectional view of the motor. Fig. 2 is also a vertical sectional view but showing the piston casting turned to a different position. Fig. 3 is a side elevation of the motor and pump with the casing of the motor broken away, showing the interior arrangement of the parts. Fig. 4 and Fig. 5 are detail views of one of the 25 pistons of the motor.

Like parts are represented by similar characters of reference throughout the several views.

Referring to Fig. 1, the inlet for the motor is indicated by a . The casing of the 35 motor is formed with a small piston cylinder at the right end and a larger cylinder at the left. I shall call the cylinder a' the small piston cylinder and the cylinder a'' the large piston cylinder. The general arrangement is such that two pistons are employed and will be called differential pistons. The same is true of the valve arrangement, there being differential pressure applied to the valves, as will be explained 40 hereinafter.

The parts are shown in Fig. 1 with the larger piston a^3 at the extreme limit of its throw to the left, and in this position the port a^4 , formed in the casing of the motor, 50 registers with a port a^5 , formed in the smaller piston a^6 . Referring to Fig. 4, it will be seen that the piston is so constructed

that an outer head or cap a^7 is screwed on the end of the valve casing a^8 .

In assembling the parts, the inner flange 55 a^9 is formed integral with the casing a^8 , and a leather, a^{10} , is readily inserted. Then the intermediate head, a^{11} , is fitted on the bore of the casing to bear against the leather, a^{10} , and the outer head, a^7 , and leather is thereafter 60 screwed into position, and a chamber, a^{12} , is formed between the intermediate head and the outer head. The port a^5 connects with the circumferential chamber, a^{12} , and when the port, a^4 , registers with the port, 65 a^5 , the live water passes into the chamber, a^{12} . From thence the live water passes through the passage, a^{13} , which is shown in Fig. 3 to be a pipe projecting from the circumferential chamber, a^{12} . The passage 70 terminates in the large valve chamber, a^{14} . The effect of this is to throw the valves, a^{15} and a^{17} , to the right, assuming the position shown in Fig. 1, since the pressure against the valve a^{15} is equalized. 75

Referring now to the specific construction of the parts, I have preferably formed the small and large piston of a solid casting, with the small and large valve cylinder formed therein, and the pipe, a^{13} , extends 80 from one end of the casting to the other, connecting the circumferential chamber, a^{12} , with the large valve chamber, a^{14} . There is formed on the top and bottom of the casting an oval shaped opening a^{16} which is 85 always connected with the water inlet, a , so that the live water can at all times enter said opening. There are also formed in this central casting passage-ways, b and b' (Fig. 2) which open into the large piston cylinder 90 or chamber. There is also formed in the casting a slotted opening, b^2 , which connects the passages, b and b' , with the small valve chamber, a^{16} , excepting when the valve a^{17} covers said opening. 95

Referring to Fig. 2, wherein the valve is at the limit of its throw to the left, it is apparent that the live water, entering through the oval opening a^{16} heretofore referred to, cannot pass into the passages, b and b' , for the reason that the small valve a^{17} is in a position to shut off the water from the slotted opening, b^2 , but when the valve is thrown to the right, as shown in Fig. 1,

and as hereinbefore just explained, the slotted opening is again uncovered so the water can then pass into the passage-ways, b and b' , and from thence passes into the larger 5 piston cylinder, bearing against the large piston on the left thereof.

It is now apparent that the pressure on the right side of the large piston is equalized by the pressure on the left side thereof and 10 therefore the pressure of the live water on the left side of the small piston a^6 forces the casting or combined pistons to the right, and the small piston is finally brought into position such that the port, c , (Fig. 2) 15 registers with the port, c' , formed in the wall of the small piston chamber. In this final position of the parts the dead water which accumulated in the large valve chamber, a^{14} , 20 may now pass back through the pipe, a^{13} , to the chamber a^{12} and from thence through the ports, c , c' , into the passage, c^2 , and thence to the outlet, c^3 . The result of this is that the pressure of the live water acts on the large valve, a^{15} , the pressure being no 25 longer equalized, forces the valve to the left and thereby forces the dead water out of the large valve chamber, a^{14} . When the valve, a^{17} , reaches the extreme left position 30 shutting off the live water, the small valve again uncovers the slotted opening in the passage walls, b and b' , so that the water on the left side of the large piston can pass through said passages, b and b' , through the slotted opening, b^8 , into the small valve 35 chamber, and thence to the small piston chamber, thence to the passage-way, c^2 , and finally to the outlet, c^3 .

From this explanation of the construction of the parts and the operation of the device 40 it will be seen that there are very few parts required to be assembled, a minimum number of leathers necessary to prevent leakage, and a minimum danger of impairment of the parts in their operation. Both the 45 pistons and the valves are dependent upon differential pressure for their operation, and by combining a differential piston device with differential valve mechanism, it is seen that the motor is greatly improved, 50 both in simplicity and in its operation.

It should be stated that preferably there is employed for the valve mechanism an integral casting formed at one end with the large valve, a^{15} , and at its opposite end with 55 the small valve, a^{17} . There is formed on the body of the valve a stop, a^{18} , and this stop is shown (Fig. 1) in contact with an offset formed in the wall of the small valve cylinder or chamber.

60 Finally, it should be remembered that both the pistons and the valves, for their operation, are dependent upon the pressure on one of the pistons and one of the valves being first equalized and thereupon the pressure 65 upon the other piston or valve causes

the piston or valve to operate, and in that sense there is here shown a combination of differential piston and valve mechanism.

Having thus described my invention, I claim:—

1. In a motor, the combination of a casing having an inlet, differential piston mechanism within said casing, and a valve device within the piston mechanism together with ports and passages constructed and arranged 70 to cause the valve device to be shifted at the end of the stroke.

2. In a motor, the combination of a casing having a fluid inlet and outlet, piston mechanism in said casing, a valve device, the piston mechanism comprising a passage for fluid for operating the valve device, provision for placing the passage in communication with the inlet, and provision for placing the passage in communication with 80 the outlet, whereby said fluid constitutes the sole means to cause the valve device to be shifted at the end of the stroke of the piston mechanism, substantially as specified.

3. In a motor, the combination of a casing 90 having an inlet, a differential piston mechanism supported within said casing, and a differential valve device within the piston mechanism together with ports and passages constructed and arranged as the sole 95 instrumentalities to cause the valve to be shifted at the end of the stroke.

4. In a motor, the combination of a casing having a fluid inlet and outlet, piston mechanism supported by said casing, a valve device, the piston mechanism comprising a passage for fluid for operating the valve device, provision comprising ports for connecting said passage with said inlet, and provision for placing said passage in communication with the outlet, whereby the fluid will constitute the sole means to cause 100 the valve device to be shifted, substantially as specified.

5. In a motor, the combination of a casing 110 having a fluid supply inlet and a discharge outlet; a piston mechanism comprising two pistons supported in said casing, said piston mechanism having a fluid chamber; a valve device carried by said piston mechanism, 115 said valve device controlling a passageway carried by the piston mechanism and leading to one side of one of said pistons to alternately place said passageway in communication with the supply inlet and the discharge outlet; provision for having said valve device in communication with said fluid chamber; provision for placing said inlet into communication with said fluid chamber at one point of the stroke of said 120 piston mechanism; provision for placing said outlet into communication with said fluid chamber at another point in the stroke of said piston mechanism; and provision for having said valve device in communication 125

with said inlet; all arranged and constructed to cause the fluid to shift said valve device at the end of the stroke of said piston mechanism in each direction.

5 6. In a motor, the combination of a casting having a fluid supply inlet and a discharge outlet; a piston mechanism comprising a large and a small piston supported in said casing, said supply inlet being adapted to discharge the fluid into said casing between the respective pistons of said piston mechanism; a valve device carried by said piston mechanism, said valve device controlling a passage-way carried by said piston mechanism and leading to one side of the large piston to alternately place said passage-way in communication with the supply inlet and the discharge outlet; provision for having said valve device in fluid communication with said piston mechanism; provision for placing said piston mechanism in fluid communication with the discharge outlet at one end of its stroke in one direction; provision for placing said piston mechanism in fluid communication with the discharge outlet at one end of its stroke in one direction; and provision for having said valve device in fluid communication with said inlet; all arranged and constructed to cause the fluid to shift said valve device at the end of the stroke of said piston mechanism in each direction.

7. In a motor, an outer casing, a piston device having two pistons located in said casing, a fluid inlet in said casing between the inner sides of the respective pistons, a valve mechanism carried by said piston device, a fluid passageway to the outer side of one of said pistons, an outlet in said casing, and means for operating said valve mechanism solely by the fluid to alternately admit and discharge the fluid through said passageway, substantially as and for the purpose specified.

45 8. In a motor, an outer casing, a piston device in said casing comprising two pistons, a fluid inlet in said casing between said pistons to maintain a constant pressure of the fluid between and on the inner sides of the same, a valve mechanism, means whereby the fluid forms the sole agency at the end of one stroke of the piston device to cause said valve mechanism to admit the live fluid to the opposite side of one of said pistons so as to equalize the fluid pressure thereon, and means whereby the fluid forms the sole agency for causing said valve mechanism to permit the discharge of said fluid from said opposite side of said piston at the end of the opposite stroke of said piston device, substantially as specified.

9. In a motor, an outer casing, a piston device in said casing comprising two main pistons, a fluid inlet in said casing between said pistons to maintain a constant pressure

of the fluid upon the inner sides of the respective main pistons, valve mechanism comprising two pistons, a fluid passageway leading to the outer side of one of said main pistons, means whereby the fluid shifts said valve mechanism at the end of one stroke of the piston device to permit the live fluid to pass through said passageway to the outer side of said main piston to equalize the fluid pressure thereon, and means for causing said fluid to operate said valve mechanism to permit the discharge of said fluid on the outer side of said main piston at the end of the opposite stroke of the piston device, substantially as specified.

10. In a motor, an outer casing, a piston device located therein, a valve mechanism comprising two pistons carried by said piston device, a fluid inlet in said casing having a communication with said valve mechanism so as to maintain a constant pressure of the fluid between the respective pistons, means whereby at the end of one stroke of the piston device a fluid communication is established to the opposite side of one of said pistons so as to equalize the pressure thereon and permit the fluid to shift said valve mechanism, means whereby the shifting of the valve mechanism causes the fluid to move the piston device, and means for permitting the discharge of the fluid from the opposite side of said valve piston through a passage-way carried by said piston device at the end of this stroke of said piston device to permit the fluid pressure between said pistons to shift said valve mechanism and thereby cause the fluid to move said piston device back to its initial position, substantially as specified.

11. In a motor, an outer casing, a piston device located in said casing, said piston device comprising a large and a small piston, a fluid inlet in said casing between the inner sides of the respective pistons, a fluid passageway carried by said piston device and leading to the outer side of said large piston, an outlet in said casing, a valve mechanism carried by said piston device, and means for operating said valve mechanism solely by the fluid to alternately form a communication between said passageway and said inlet and said passageway and said outlet, substantially as specified.

12. In a motor, an outer casing, a piston device in said casing comprising a large piston and a small piston, an inlet in said casing between the inner sides of the respective pistons, a passageway carried by said piston device leading to the outer side of said large piston, an outlet in said casing, a valve mechanism carried by said piston device comprising a large piston and a small piston, a fluid communication between the inner sides of said valve pistons, a passageway carried by said piston device and lead-

ing to the outer side of said large valve piston, means for alternately forming a communication between said valve passageway and the fluid inlet and between said valve 5 passageway and the fluid outlet to cause said valve mechanism to alternately establish a communication between said piston passageway and the fluid inlet and said pis-

ton passageway and the fluid outlet, substantially as specified.

In testimony whereof, I have hereunto set my hand this 15th day of March 1909.

JESSE C. HOWARD.
